UNITED STATES PATENT OFFICE.

BENOIST P. GILMAN, OF YOAKUM, TEXAS.

DRIFT VALVE.

1,401,975.

Specification of Letters Patent.

Patented Jan. 3, 1922.

Application filed March 1, 1918. Serial No. 219,911.

To all whom it may concern:

Be it known that I, BENOIST P. GILMAN, a citizen of the United States, residing at Yoakum, in the county of Lavaca and State 5 of Texas, have invented new and useful Improvements in Drift Valves, of which the following is a specification.

This invention relates to drift valves for locomotive engines and the main object of 10 the invention is to produce a valve which will effect an automatic diversion of the exhaust steam from the air pump of the locomotive from the normal outlet to the stack or smoke box, into the steam chests of the 15 steam cylinders, after the steam from the main throttle has been shut off and the engine is drifting, coasting or running without using steam as in descending grades. The exhaust steam containing oil from the 20 air pump is then delivered into the steam chests through the operation of the drifting valve, thus furnishing the necessary lubrication for the cylinders and pistons.

With the above and other objects in view, 25 the invention consists in the novel construction, combination and arrangement of parts, as herein described, illustrated and claimed.

In the accompanying drawings:

Figure 1 is a longitudinal section through 30 the drifting valve.

Figure 2 is a section through the same on the line 2—2 of Figure 1.

Figure 3 is a detail view of the drifting valve proper, detached.

Figure 4 is a view of the steam chest manifold including the line check.

Figure 5 is a diagrammatic view of the entire apparatus.

Figure 6 is a view showing the invention 40 in use upon a locomotive.

Referring to the drawings, A designates the drifting valve proper and B the casing in which said valve is mounted for reciprocatory movement. The valve A comprises 45 a tubular or sleeve-like body 1 and has at one end thereof, an enlarged piston head 2, the latter having expansion rings 3 of the split type. The piston head 2 is formed with a central cavity or recess 4 against 50 which the steam pressure acts as will hereinafter appear, and the tubular body 1 is formed with a circular series of ports 5 which preferably extend obliquely or spirally so as to prevent scarring the bushing 55 within which the body of the valve works. The body 1 is also formed with grooves to

receive split expansion rings 6 and 7, the ring 7 being located about centrally of the body 1 and the ring 6 being located adjacent to the opposite end of the body from 60 the piston head 2.

The valve casing B comprises a valve chamber 8 in which is arranged a bushing 9 which surrounds the body 1 of the valve and said bushing 9 is formed with two series 65 of ports 11 corresponding in shape and in all other respects with the ports 5 of the valve body. To prevent relative rotation between the valve body and the bushing 9, a dowel pin or key 10 is inserted through the 70 bushing, the inner end of said pin or key working in the groove or guideway 12 extending longitudinally of the outer face of the body 1 of the valve.

The valve casing B is formed at one end 75 with an extension 13 having an annular recess or seat 14 containing an expansion spring 15, the free end of which bears against the adjacent end of the valve body 1 and has a normal tendency to move said 80 valve to the right in Figure 1. At the opposite end of the valve casing B there is a steam chamber or fluid pressure chamber 16 to which the steam pressure is admitted through a pipe 17 as hereinafter described. 85 The chamber 16 is shown as having a threaded connection at 18 with the main body of the casing B. 19 designates the exhaust pipe or connection from the steam pump of the locomotive which delivers the 90 oil laden steam from the pump into the valve casing.

The casing B is formed with two annular exhaust or outlet chambers 20 and 21 which communicate through ports α in the inner 95 walls thereof with the valve chamber. The chamber 20 is in communication with a pipe 22 which leads to the steam cylinders. The exhaust chamber 21 is in communication with another pipe 23 which leads to the 100 stack. The pipe 22 is bifurcated to form a manifold embodying twin branches 24 which lead to the steam cylinders. With the valve A in the position shown in Figure 1, the exhaust steam from the pump passes from 105 the inside of the valve through the ports 5, 11, and α into the annular chamber 21 and then through pipe 23 to the stack. When the valve A moves to the right in Figure 1 it uncovers the other series of ports 11 in the bushing 9 and the exhaust steam then passes 110 through these ports and ports α into the

annular chamber 20 and through pipe 22 and its branches 24 to the steam chests. Incorporated in the pipe 22 is a back-pressure check valve or line check 25 to prevent boiler pressure from backing up from the steam chests when the engine throttle is opened.

Pipe 17 is provided with a choke plug 17* at its point of connection with chamber 16 10 and said pipe 17 is connected with pipe X which has one end connected with a steam cylinder and its other end located in the cab where it is connected with a source of steam supply, such as the steam dome X'. The 15 flow of steam from the dome into the pipe is controlled by a suitable valve so that the engineer can regulate the flow of steam into the pipe. A check valve 17' is placed in the said pipe X adjacent the cylinder, said valve 20 closing toward the cylinder so that it will be open when the main throttle is open and steam is flowing to the cylinders. This valve is closed when the engineer's valve in pipe X is open. A pet cock D is provided to 25 drain chamber 16. This pet cock and the pipe X and its controlling valve permits steam to pass through the device to prevent freezing of the water of condensation in cold weather, for by opening the pet cock to 30 a limited amount and opening the valve near X' in pipe X to permit steam to pass through said pipe and chamber 16, the parts will be heated. The flow of steam through the parts is controlled by the amount of 35 opening of the pet cock D and the control valve near X' of pipe X.

The operation of the device is as follows: When the throttle is open the pressure from the steam chests, passing through the outer 40 part of pipe X and pipe 17, and entering the valve chamber through the choke plug forces the piston valve to the extreme limit of its travel in its cylindrical casing, as shown in Figure 1. The choke plug referred to insures the entering of steam pressure at a slow enough rate to prevent severe ramming of the valve, or the forcible throwing of the same against the end of the casing. The spring referred to contributes by its cushioning resistance to the same end. Therefore, in the normal or running position, the exhaust from the air pump passes through the ports 5, 11 and 22 into chamber 21 of the valve and through pipe 23 to the stack. 50 When the engine throttle is shut off and the valve near X' in pipe X closed, there being no pressure in front of the valve, the exhaust from the pump forces the valve to the opposite position or the limit of its travel, the 55 spring referred to assisting in such operation. In this position of the parts, the ports leading to chamber 21 are closed and those leading to chamber 20 are opened, thus permitting the exhaust from the pump to pass 60 through the pipes 22 and 24 to the steam

cylinders. By this means the cooling and lubrication of the cylinders is effected. The opening of the locomotive throttle valve will force the valve back to its normal position and cause the pump exhaust to pass into the 70 stack. The line check in pipe 22 leading to the steam chest operates to prevent boiler pressure backing up from the steam chest when the engine throttle is open.

It will thus be seen that the object of the 75 valve is to divert the pump exhaust from the stack into which the exhaust normally goes when the engine throttle is shut off to the cylinders.

When an engine equipped with this device 80 comes to a prolonged stop at stations or elsewhere, the pressure accumulating in the steam chests, and cylinder from the exhaust of a rapidly working air pump may crowd the pressure in the steam chests and cylinders to such an extent as to slow up the pump. This condition can be relieved by the engineer opening the control valve near X' in pipe X and thus forcing the valve A 85 back to its normal position so that the 90 pump exhaust will pass to the stack.

It will thus be seen that the engineer can, by opening the valve near X' in pipe X, 95 force the valve A to the position shown in Figure 1, which is its normal position, so that the exhaust from the pump will pass to the stack, this effect being the same as when the main throttle is open and steam is passing through the cylinders.

I claim:

1. A drifting valve, comprising a valve casing having two annular outlet chambers surrounding the same, arranged side by side and communicating therewith, a valve body mounted for reciprocating movement in said casing, means for admitting steam under pressure from the cylinder feed chest against one end of said valve to shift the same in one direction, means for automatically shifting the valve in the opposite direction in the absence of steam pressure, a pump exhaust connection leading into one end of said valve casing, an outlet connection leading from one of said annular outlet chambers to the stack, and another outlet connection leading from the other annular outlet chamber to the steam chest of the engine, said valve controlling both of said annular outlet chambers in the back and forth movement thereof.

2. A drifting valve, comprising a valve casing having two annular outlet chambers surrounding the same, and arranged side by side and communicating therewith, a valve body mounted for reciprocating movement in said casing, means for admitting steam pressure from the cylinder feed chest against one end of said valve to shift the same in one direction, means for automatically shifting the valve in the opposite direction in 130

the absence of said steam pressure, a pump exhaust connection leading into one end of said valve casing, an outlet connection leading from one of said annular outlet chambers to the stack, and another outlet connection from the other annular outlet chamber to the steam chest of the engine, said valve having a central bore to receive the exhaust from the pump connection and being 10 formed with a single series of lateral out-

let ports from said bore, and the valve casing having two sets of outlet ports to said annular outlet chambers with one set of which the single set of ports of the valve body is adapted to register, said valve body 15 being also adapted to uncover the remaining set of outlet ports of the valve casing.

In testimony whereof I affix my signature.

BENOIST P. GILMAN.
